Primary Examiner — Daniel Bui(74) *Attorney, Agent, or Firm* — Stephen R. Yoder, Esq.**CLAIM**

The ornamental design for a sealing boot splice adapter, as shown and described.

DESCRIPTION

FIG. 1 is a front perspective view of a sealing boot splice adapter showing our new design;

FIG. 2 is a back perspective view thereof;

FIG. 3 is a top plan view thereof, the bottom plan view, the right and left side elevation views being a mirror image thereto;

FIG. 4 is a front elevation view thereof;

FIG. 5 is a back elevation view thereof;

FIG. 6 is a back perspective view thereof, in use condition; and,

FIG. 7 is a front perspective view thereof.

The broken line portion of the figure drawings is included for the purpose of illustrating environment and forms no part of the claimed design.
